OVERHEAD TRANSPORTING DOOR FOR
GARAGES AND THE LIKEGordon Raymond Coulson, Calgary, Alberta,
Canada

Application August 31, 1945, Serial No. 613,744

3 Claims. (Cl. 268—59)

1

This invention relates to an overhead door for a garage or the like of the type in which a door is raised by power-operated means and is supported and guided in tracks extending vertically at each side of the door opening and horizontally or substantially horizontally away from the top of the door opening. Most arrangements for raising doors of this type depend on cables or other flexible means connected to the bottom of the door and adapted to be wound on a power driven winding drum and they are subject to the disadvantage that a very considerable force is necessary to open and close the door. Various proposals have therefore been made for counter-balancing such doors with the aid of springs, weights and the like, but such mechanism takes up valuable space near the door opening and moreover does not dispose of the principal difficulty with known doors of this type, namely that they operate at a great mechanical disadvantage.

In the initial stages of lifting a door of the kind described there is required to be applied to the top of the door in a substantially horizontal direction a force component which is greater than that applied in a vertically upward direction and, in the later stages of lifting, the force component directed vertically upwards must be greater than that applied in a substantially horizontal direction. According to the present invention the total force available is applied simultaneously to the top and bottom of the door and is automatically distributed between the two in accordance with the resistance to movement of the top or bottom of the door, as the case may be, the tracks at each side of the door extend vertically from a point near the bottom of the door opening to a curve above the door opening and then substantially horizontally away from the plane of the door frame so that the weight of the door may be partly transferred to the horizontal track in the initial opening movement of the door, and cable to be wound on a drum is arranged as hereinafter set forth whereby the greatest mechanical efficiency results. The necessity for the provision of reinforcing cables, weights, springs or levers is obviated, and the size, weight and cost of all the mechanical parts of the instant device are greatly reduced, while the operations of raising and lowering a heavy door are always effected with the maximum ease and efficiency. The instant invention is thus essentially differentiated from prior structures in that the effort needed to raise and lower the dead weight of a door is automatically applied to the door at different points and in different directions during its transpor-

2

tation, these points being at each stage of the operation those at which the maximum mechanical advantage is obtained.

According to the invention, therefore, there is provided the combination in an overhead door structure of a door frame defining an opening, tracks at each side of the door opening extending vertically from a point near the bottom of the door opening to a curve above the door opening and then substantially horizontally away from the plane of the door frame, a door, bearing members at each side of the door co-operating with said tracks, cable winding means fixedly mounted near the top of the door opening, and cable means extended from the top of the door to said winding means and, between the top of the door and the winding means, over at least one pulley mounted at each of the following stations: a fixed portion of the structure horizontally removed from the top of the door opening and at approximately the level of the top of the door opening, a fixed portion of the structure adjacent the top of the door opening, and a portion of the door adjacent the bottom thereof, the cable means being trained over said pulleys in that order and passing upwardly from the last mentioned station to the winding means.

The cable means preferably comprises a single cable having each end connected to the winding means adjacent each side of the door opening, the cable being slidably connected between its ends to the top of the door at each side thereof, so that if one drum winds in cable faster than the other, as a result, for example, of the cable piling up instead of being evenly wound on the drum, cable will be passed from one side of the door to the other and the pull on the two sides of the door will be equalized.

The result of this construction is that cable equal to four times the height of the door is trained over the pulleys at each side of the door and three quarters of this cable is wound in during the movement of the door from fully closed to fully open position. The over-all mechanical advantage is therefore 3:1. The initial lift is accomplished with a mechanical advantage of 2:1 and as the opening of the door progresses, this mechanical advantage increases rapidly and then diminishes, but is never less than 2:1.

As a prime mover, any type of means may be employed such as hand-chains in connection with suitable gearing, or an electric, pneumatic or hydraulic motor. The invention may be applied to a door which consists of a single closure member and to one having any number of horizontal

door sections suitably articulated, such as are commonly installed in airdrome hangers and grain elevators.

The invention will now be described with reference to the accompanying drawings in which:

Figure 1 is an elevation of the door, seen from inside the building,

Figure 2 is a partly sectional side elevation taken on the line 2—2 of Figure 1,

Figure 3 is a detail of a portion remote from the door of the opposite trackway to that shown in Figure 2,

Figure 4 is a plan of the power operating means and illustrates the relation of the door to its housing including the surrounding wall and the door jamb,

Figure 5 is a fragmentary plan detail showing a cable pulley fixed to the upper part of the door through which the horizontal force components is applied to the door,

Figure 6 is a sectional elevation taken on the line 8—8 of Figure 4, looking in the direction of the arrow,

Figure 7 is an enlarged section taken on the line 9—9 of Figure 6,

Figure 8 is a fragmentary view on the line 10—10 of Figure 1,

Figure 9 is a fragmentary partly-sectional detail of a cable pulley on the lower part of the door.

Figure 10 is a fragmentary view of a wedging means adjacent the lower end of a trackway,

Figure 11 is a sectional detail of a winding drum and its shroud.

Figure 12 is a diagram illustrating the operation of the door, and

Figure 13 is a side elevation on a reduced scale, taken in the direction of the arrow in Figure 8.

By referring first to Figure 12, the principle of operation of the door will be understood. In this diagrammatic figure, for clarity, the door is represented as a unit, but it will be understood that the operating principles apply equally in cases where as in Figure 1 the door comprises a number of horizontal, articulated door panels. The numeral 20 indicates one of a pair of plates fixedly secured as at 21 adjacent to each side of the door. Journalled in each plate is a spindle 22 having winding drums 23 and 31 fixedly secured thereon. One end of a cable 24 is secured to the drum 23. The cable is led directly from the drum 23 and reeved around the pulley 25 secured to the lower part of one side of the door 26, over the idler pulley 27 journalled to the plate 20, and continues around the pulley 28 secured adjacent to the outer extremity of a substantially horizontal portion 29 of a trackway 40 disposed adjacent to each side of the door 26. The horizontal portions 29 of each trackway project above the door from the wall 21 and are similarly inclined upwardly at the outer ends, to facilitate downward movement of the door during closing operations. After passing round pulley 28, the cable is returned to a pulley 30 mounted on the upper part of door 26. The cable is then led across the door and disposed in connection with correspondingly arranged pulleys mounted on the other side of the door and on the other bracket and trackway, the end of the cable being finally secured to the drum 31, seen in Figure 1.

It will be appreciated from Figure 12 that as the door is raised from closed position, the lower end 32 of the door moves at a slower rate of speed than does the top of the door 26. In the same time that the bottom of the door moves from the

points A to A1, in the vertical portions of the trackways, the top of the door moves from B to B1 along the upper portions of the trackways. The bottom of the door has thus moved up the vertical trackways 33, substantially one half of the distance that the top of the door has moved along the upper trackways 29, in the same time. Since both ends of the cable 24 are simultaneously wound onto the drums 23 and 31 during the revolution of the spindle 22, the transporting effort is applied to the door simultaneously via the corresponding pulleys 30 and the corresponding pulleys 25. As the effort required to move the door horizontally from B to B1 is less than that required to move the door vertically from A to A1, the greater part of the total effort available is applied to pulling the points B1 towards the pulleys 28 and thus during this part of the transportation, a mechanical advantage is obtained.

If, after pulleys 30 reach the corresponding points B1, the greater part of the available effort were continued at the points B1, such effort would be applied at an increasing mechanical disadvantage. At this stage of the operation, less effort is required to raise the door by lifting the lower end 32. Accordingly, the greater part of the effort is automatically transferred by the cable from the points B1 and is exerted on the door at the points A1 via the corresponding pulleys 25. The result is that between the points A1 and B the greater part of the available effort applied by the spindle 22 to the cable 24 is employed as a vertical upwardly directed force component which causes the bottom of the door to be lifted from the points A1 in the vertical trackways substantially to the points B at the inner ends of the substantially horizontal trackways. The top of the door is simultaneously transported to corresponding points C adjacent to the pulleys 28. In this position the door is fully open and it is evident that a mechanical advantage is obtained during the entire period of transportation.

Similarly, when the movement of the spindle 22 is reversed, the cable 24 is paid out by both drums and gravity exerts a diminishing downward pull on the door, more particularly on that part adjacent pulleys 25. The inclination of the upper trackways facilitates the movement of the rollers on the trackways during this phase of movement of the door. When the pulleys 25 reach the points A1, the greatest effort is automatically transferred to the pulleys 30, which are now at the points B1 in the trackways, this effort continuing until the pulleys 30 reach point B, at which position the door is fully closed and is once more vertical. The curve at the junction of the vertical and horizontal portions of each trackway helps to maintain smooth movement of the rollers in the trackways during the last stage of a downward transportation and also during the initial stages of an upward transportation. The last phase of the movement of the pulleys 30 around such curved sections of the trackways also urges the top part of the door to close against the wall housing.

As will be evident from consideration of the plan of the door and its housing in Figure 4 provision is made firmly to close the edges 120 of the door both against the floor 121 and against its housing. The latter includes door jambs or stops 122 which extend around the two sides and across the top of the outside of the door opening. Properly to position the bottom edge 123 of the door against the floor of the opening, depressions

[124', Fig. 1 are formed in the floor 121. These are of sufficient size and depth freely to accommodate the cable pulleys 25 which project slightly beyond the bottom edge of the door. When the door is in vertical, closed position, the bottom horizontal edge 123 of the door 26 is thus flush with the surface of the floor.

As best seen in Figs. 1, 2 and 8 to close the door laterally against the side stops 122 during the later stages of a downward transportation, apparatus at each side of the door generally indicated by numeral 125 is provided. By reference to Figure 2, it will be seen that the vertical portions of the trackways are supported in relation to the wall 127 by brackets 126 while the top portions of the track-ways are supported from the roof by hangers 128. The brackets 126 are secured to the wall 127 as by members 129 substantially at intervals corresponding to the points of contact of the vertical tangents to the guide rollers 130 and 131. The latter are mounted on spindles 132 which in the case of an articulated door form the hinge pins between separate sections as 133 and 134 of the door. The brackets 126 are provided adjacent their extremities and remote from the wall of the building, with substantially horizontal bores 135. Through each bore 135 a spindle 136 is disposed. The latter are each provided with a slotted lever 138 projecting radially from the end of the spindle remote from the guide rollers 130 and 131. At the opposite end of each spindle 136 an eccentric cam 137 is secured. Rotation of spindles 136 by the levers 138 thus rotates the cams 137. Connected to each lever 138 is a link rod 139 disposed as seen in Figure 1 in a generally vertical position, and normally urged by spring 140 in a direction away from the floor 121. Pins 141 secured to the shank of the rod 139 pass through the slots 142 in the levers 138 and connect the rod 139 with the levers 138.

Secured to the bottom portion of the rod 139 as by member 197, is a projection 143 disposed with its long axis in the direction of the door 26. Projection 143 is of sufficient length to be engaged by the bottom edge 123 of the door during the later stages of downward transportation movement of the latter. Elongated orifices 150 are formed in the vertical portions of the trackways disposed in positions substantially corresponding with the guide rollers 130 and 131 in accord with the position of the latter when the door is in closed position.

When during downward movement of the door the bottom edge 123 of the door engages the projection 143, the link rods 139 are pushed downwardly against the tension of spring 140 to rotate the eccentric cams. The peripheral portions of the latter are thus caused to project progressively into the apertures 150 in the trackways. When the door is lowered sufficiently, the cams engage the guide rollers and force them inside the trackways in the direction of the door housing. This action continues until the edges 120 of the door as seen in Fig. 4, are firmly wedged by the action of the cams against the wall jambs 122.

To aid this wedging action, the lower vertical portions of the trackways are provided (Fig. 10) with inclined portions 151, each having an inclined surface 152 of which the lower portion projects towards the door and functions when engaged by the rollers to urge the guide rollers and door in the direction of the door jambs. Such wedge means may be formed integral with the trackway but preferably consists of wedges

formed separately and secured one at the bottom end of each trackway.

To prevent the door from sagging when it is in horizontal positions where it is entirely supported by the trackways, tie rods 153 are disposed horizontally across the inner face of the door. These are secured at convenient vertical intervals by means of suitable angle members 154 which are connected to the rods 153 and secured to the door as at 155.

By reference to Figures 4-7 inclusive, the mechanical details of the brackets 156 supporting the upper pulleys 30 will be understood. Each bracket 156 is formed with a pair of projecting members 157 and 158, correspondingly bored on a horizontal axis to receive a spindle 159.

On the outer ends of spindles 159 are also mounted guide rollers 170, one being located in each trackway 29. Also mounted on each spindle 159 is an idler pulley 169, disposed with its sheave in alignment with the portion 162 of the cable 24, to act as a guide for the latter (Fig. 5). An orifice 163 is formed in the centre part of the projections 157 and 158 through which the cable 24 passes to the other side of door, to facilitate the equal distribution of the horizontal and vertical forces applied by the cable to each side of the door. The cable pulleys 30 are mounted on each outer projection 157, the axis of rotation of these pulleys being vertical. Each pulley 30 (Figure 9) is rotatably mounted on a spindle 159 secured between the retaining members 160 and 161. The latter are suitably secured as by the welds 162 and 163 to the outer sides 164 of the projections 157. As the cable 24 rides over pulleys 30, at opposite ends of the upper part of the door, the latter thus compensate for any slight difference of pull which may be exerted on the door from opposite ends of the cable, due to any slight difference in the speeds of rotation of the drums 23 and 31.

Where a door is composed of horizontal sections as 133 and 134, the guide rollers 130 and 131 are secured at the outer extremities of spindles, which form the pins of the hinges 183 between each door section. In the case of the guide rollers 170 and 171, their spindles 159 and 172 respectively are journalled in brackets 156 and 173 respectively, secured by members 184 to the top and bottom of each side of the door. The preferred sectional form of the guide rollers and trackways is seen in Figure 8. These latter are formed with a lip 174 of a height less than the radius of the guide rollers and disposed at the inner edges of the trackways. The total inside height of each trackway is of course, greater than the diameter of the rollers as the difference between these dimensions determines the extent to which the door can be laterally closed against the stops 122 by operation of the apparatus 125. In all positions of the door, the guide rollers and corresponding spindles are clear of the lips 174.

To ensure that the cable is wound evenly on to the drums, the winding drums 23 and 31 (Figure 11) are provided with shrouds 175, each having an opening 176 of a size adequate to receive the cable. It will be seen from Figure 4 that reduction gearing R in connection with the motor is provided. The input shaft 186 turns at motor speed and is connected to one end of the reduction train of R. The output shaft 22 of the reduction train turns at a substantially reduced speed by the virtue of the reduction gearing R. The ratios between the speeds of shafts 186 and 22 can be varied to suit the special requirements

of different doors by changing the sizes of the sprockets 187 and 188, or by changing the gear ratios of R or by changing the diameters of the winding drums.

What I claim is:

1. The combination in an overhead door structure of, a door frame defining an opening, tracks at each side of the door opening extending vertically from a point near the bottom of the door opening to a curve above the door opening and then substantially horizontally away from the plane of the door frame, a door, bearing members at each side of the door co-operating with said tracks, cable winding means fixedly mounted near the top of the door opening, and cable means extended from the top of the door to said winding means and, between the top of the door and the winding means, over at least one pulley mounted at each of the following stations: a fixed portion of the structure horizontally removed from the top of the door opening and at approximately the level of the top of the door opening, a fixed portion of the structure adjacent the top of the door opening, and a portion of the door adjacent the bottom thereof, the cable means being trained over said pulleys in that order and passing upwardly from the last mentioned station to the winding means.

2. The combination in an overhead door structure of, a door frame defining an opening, tracks at each side of the door opening extending vertically from a point near the bottom of the door opening to a curve above the door opening and then substantially horizontally away from the plane of the door frame, a door, roller members at each side of the door co-operating with said tracks, at each side of the structure a series of pulleys comprising a pulley mounted on a fixed

5 10 15

portion of the structure horizontally removed from the top of the door opening and at approximately the level thereof, a pulley mounted on a fixed portion of the structure adjacent the top of the door opening and a pulley mounted on a portion of the door near the bottom thereof, cable winding means fixedly mounted near the top of the door opening and cable means extended from the top of the door at each side thereof over one of the series of pulleys and passing upwardly from the last-mentioned pulley of each series to the winding means.

3. The combination as defined in claim 2 in which said cable means comprises a single cable having each end connected to said winding means adjacent each side of the door opening, the cable being slidably connected between its ends to the top of the door at each side thereof.

GORDON RAYMOND COULSON.
